APPARATUS FOR LEVELING OR STRAIGHT-
ENING METAL SHEETS

Eugene Mayer, Strasbourg, France

Application December 23, 1947, Serial No. 793,379
In France March 12, 1940Section 1, Public Law 690, August 8, 1946
Patent expires March 12, 1960

4 Claims. (Cl. 153—93)

1

The straightening of metal sheets of high quality is carried out in practice either by roller levellers or by stretching machines. Neither type of apparatus is, however, free from defects. The levellers have a large output and enable sheets to be flattened in packs of two, three, or more at a time. As the sheets are passed through the levellers in a lengthwise direction, the latter can be placed in line with other continuously operated machines in which the sheets undergo treatment, such as shears, oiling machines, etc. Frequently, however, the straightening effect obtained is not entirely satisfactory and, at any rate, not sufficient when the sheets are to be perfectly flat, as is required, for instance, for sheets which are to be used in the manufacture of office furniture. Besides, it is not possible by straightening sheets on a roller leveller to free the sheets entirely from the internal stresses which are set up during the preceding rolling and annealing stages.

Stretching machines, on the other hand, give very good results as far as the straightening in itself is concerned, but their output is small and the feeding of the sheets into the machines and their discharge therefrom are rather complicated. Furthermore, the jaws of the stretching machines which hold the sheets at their ends are liable to leave marks thereon, so that it is necessary to shear off the sheet ends, with a consequent loss of material.

The object of the present invention is to provide a method and apparatus which are capable of levelling and stretching metal sheets in one single operation, and which have the advantages of the two above methods and machines without their limitations.

The apparatus according to the present invention, comprises two or more roller leveller units arranged in one line and so close to each other that a sheet will enter one unit before it is released by another one, at least one of the units being capable of exerting a stretching force on the sheet through the intermediary of the leveller rollers so that a sheet is subjected simultaneously to a stretching and to a levelling operation whilst it is engaged by and advanced through two leveller units at a time.

In the following examples, only the most simple of various forms in which the invention can be carried out will be described, viz., the one in which the apparatus consists of two leveller units only. It is, however, to be understood that the provision of more than two leveller units in one and the same apparatus comes within the scope of the present invention.

2

The stretching force on the sheet can be produced in two different ways, either by giving to the rollers of the second leveller unit a higher surface speed than to those of the first one, or by increasing the distance between the two leveller units whilst the sheet is gripped by both units.

The difference in surface speed between the rollers of the second and the first units can be achieved in a very simple manner by rotating the 10 rollers of the second unit faster than those of the first unit, the speed of the second unit being adjustable if desired; or, alternatively, by fitting the second unit with rollers of larger diameter than the first one, or by any other suitable means.

15 In cases where ordinary commercial sheets are to be handled, the connection between the two units may be rigid. For higher quality sheets, however, a non-rigid connection between the two units is to be preferred, inasmuch as the pull 20 exerted by the second unit on the sheet tends to draw the two units together. A rigid connection between the two units would then cause the sheet to slide past the rollers, if the pull on the sheet is too strong. This would result in the sheet being 25 marked, which, whilst of no great consequence for ordinary commercial sheets, would constitute a serious defect in high quality sheets.

A non-rigid connection between the two units 30 can be achieved by any means which will resist the approach of the two units towards each other. These means may be purely mechanical, embodying, for instance, springs, or they may be hydraulic or pneumatic. The means should preferably further include a return mechanism which 35 may be formed by springs, so that the second unit is brought back into its initial position as soon as a sheet has passed through the apparatus. The force which resists the approach of the two units towards each other may be made adjustable.

40 Reverting to the second of the two alternatives for producing a stretching force on the sheet, the increase of the distance between the two units may be effected by purely mechanical means, such 45 as a threaded spindle, or, by hydraulic, pneumatic or other means. Here again, it is preferable to provide a return mechanism for the afore-mentioned purpose.

45 It is further possible to incorporate into an apparatus according to the invention both the above-described alternatives for producing a stretching force on a sheet.

50 The invention will now be described with reference to the accompanying drawings, which are, however, only to be regarded as illustrating ex-

amples and in no way as limiting the scope of the invention:

In the drawings:

Fig. 1 is a vertical section through one form of apparatus according to the invention, in which the stretching force is effected by giving the rollers of the second unit a higher surface speed than those of the first unit.

Figs. 2 and 3 are details of a component of the apparatus according to Fig. 1 in two different positions.

Referring first to the apparatus shown in Fig. 1, a common frame 10 carries two leveller units 11 and 12 having separate housings which have top and bottom rollers 13 and 14, and 15 and 16 respectively. The rollers 13 and 15 are staggered relative to the rollers 14 and 16 respectively as is usual in conventional roller levellers. All the rollers are power-driven through gears of conventional design which are, however, not shown here for the sake of simplicity, the drive being such that the rollers 15 and 16 of the second unit turn at higher surface speeds than the rollers 13 and 14 of the first unit. The unit 11 is rigidly secured to the frame 10, whilst the unit 12 is adapted to move in guideways 17 of the frame 10.

The housing 18 of the second unit 12 has a downward extension 19 which passes through a recess 20 in the top of the frame 10. A spindle 21 is threaded into the extension 19 and carries at one end a piston 22 which slides in a cylinder 23. The cylinder is filled with a liquid of suitable viscosity. Arranged in the piston 22 are narrow ducts 24 which allow the liquid in cylinder 23 to pass slowly from one side of the piston 22 to the other. The wall of the cylinder 23 has a hole 25 which is of larger diameter than the ducts 24 and leads into a channel 26 provided in the wall of the cylinder parallel to its axis and permit liquid to flow from one side of the piston 22 to the other, so as to by-pass the piston. The flow of liquid through this channel is controllable by a hand-operated valve 27. A return spring 28 is inserted between the cover of the cylinder 23 and the extension 19.

The apparatus is operated as follows:

A sheet S is fed into the two leveller units 11 and 12 as shown in Fig. 1, and is simultaneously flattened by the rollers 13, 14 and 15, 16 and stretched between the two units, the stretching force being applied to the sheet in the plane of the sheet through the intermediary of the rollers themselves, since the rollers 15, 16 rotate at a higher surface speed than the rollers 13, 14. The reaction to the stretching of the sheet produces a force in the second unit 12 which tends to displace the same in the direction of the arrow F. This movement of the unit is, however, slowed down by the spring 28 and by the fluid displaced by the piston 22 in the cylinder 23. The rate of movement of the second unit 12 is dependent on the aperture at the outlet end of the by-pass channel 26 which aperture is controlled through the valve 27. The further the valve 27 enters the opening of the by-pass channel 26, the slower will be the movement of the unit 12.

When the valve 27 has closed the aperture completely, the liquid in the cylinder 23 can only flow through the narrow ducts 24, which offer considerable resistance to the flow of the liquid and thus produce the maximum braking force on the unit 12.

After the sheet has left the second unit 12, the spring 28 will return the same into its initial position. This spring has, therefore, a dual func-

tion; during the actual stretching operation it serves to increase the braking force on the movable leveller unit, whilst after the stretching operation it serves to return the movable leveller unit into its initial position.

In the above-described apparatus, the leveller unit 12 will return to its initial position at the same slow rate at which it moved forward during the stretching operation under the influence of the pull exerted by the sheet S. It is, however, desirable that the return movement of this unit should occur at a faster rate, and this can be effected by means of the non-return valve shown in Figs. 2 and 3. This valve is attached to the piston 22, has a bore 29 of larger cross-section than the two ducts 24, and is adapted to be closed by a cone 30 when the piston 22 moves in the direction of the arrow G, Fig. 2, and opened when the piston 22 moves in the direction of the arrow H, Fig. 3. The resistance developed by the viscous fluid in the cylinder 23 during the return movement of the piston is, therefore, very small, and the return movement will take place at a comparatively high speed.

In the drawings, only one cylinder 23 is shown, but it is preferable to provide two cylinders instead, arranged symmetrically with respect to the plane of the sheet S, in order to avoid the formation of a couple of forces which would tend to tilt the sheet.

I claim:

1. An apparatus for straightening metal sheets comprising at least two sets of rollers arranged in tandem, each set consisting of two superimposed horizontal rows of rollers, the rollers of one row being staggered relative to those of the other row and the two sets being positioned near enough to each other to permit the sheet to be engaged by the rollers of one set prior to being released by the rollers of the other set, a housing supporting the first set of rollers, a housing supporting the second set of rollers, a frame, the first of said housings being secured to said frame and the second of said housings being slidable on said frame, power means for rotating rollers of both sets simultaneously but at different speeds, whereby a stretching force is applied to the sheet in the plane of the sheet and the moveable housing is drawn towards the fixed housing whilst the sheet is engaged by and advanced through both sets of rollers at a time, and elastic means opposing the approach of said moveable housing to the fixed housing.

2. An apparatus for straightening metal sheets comprising at least two sets of rollers arranged in tandem, each set consisting of two superimposed horizontal rows of rollers, the rollers of one row being staggered relative to those of the other row and the two sets being positioned near enough to each other to enable a sheet to be engaged by the rollers of one set prior to being released by the rollers of the other set, a housing supporting the first set of rollers, a housing supporting the second set of rollers, a frame, the first of said housings being secured to said frame and the second of said housings being slidable on said frame, power means for rotating the rollers of both sets simultaneously but at different speeds whereby a stretching force is applied to the sheet in the plane of the sheet and the moveable housing is drawn towards the fixed housing whilst the sheet is engaged by and advanced through both sets of rollers at a time, elastic damping means opposing the approach of said moveable housing to said fixed housing and spring means

for returning said moveable housing into its initial position after the sheet has been released by the first set of rollers.

3. An apparatus for straightening metal sheets comprising at least two sets of rollers arranged in tandem, each set consisting of two superimposed horizontal rows of rollers, the rollers of one row being staggered relative to the rollers of the other row and the two sets being positioned near enough to each other to enable a sheet to be engaged by the rollers of one set prior to being released by the rollers of the other set, a housing supporting the first set of rollers, a housing supporting the second set of rollers, a frame, the first of said housings being secured to said frame and the second of said housings being slidable on said frame, power means for rotating the rollers of both sets simultaneously but at different speeds, whereby a stretching force is applied to the sheet in the plane of the sheet and the moveable housing is drawn towards the fixed housing whilst a sheet is engaged by and advanced through both sets of rollers at a time, a hydraulic damping cylinder, a piston displaceable in said cylinder and connected to said moveable housing, said piston having one or more passages to permit the flow of fluid from one side of the piston to the other, and a non-return valve constraining the flow of liquid through said passages only when said moveable housing is drawn towards said 30 fixed housing.

4. An apparatus for flattening metal stock, comprising at least two sets of straightening rollers through which the stock is passed in succession, said sets being disposed so close to each other that the stock is engaged by the rolls of the second set prior to its release from the first set, one of said sets being capable of a movement towards and away from the other set; means for rotating the rolls of the second set at a higher 10 surface speed than the rolls of the first set, whereby the movable set is drawn towards the other set while the stock is engaged by both sides; and means for applying a force to the movable set opposing the approach of the movable set to the other set, whereby the sheet is subjected to a stretching action.
